W. F. KOKEN.
PEDESTAL BASE FOR BARBER CHAIRS.
APPLICATION FILED MAR. 31, 1919.

Patented Apr. 20, 1920.

10 Inventor,
Walter F. Koken.
By Bushnell & Knoblauch.

UNITED STATES PATENT OFFICE.

WALTER F. KOKEN, OF ST. LOUIS, MISSOURI.

PEDESTAL-BASE FOR BARBER-CHAIRS.

1,337,608.

Specification of Letters Patent. Patented Apr. 20, 1920.

Application filed March 31, 1919. Serial No. 286,354.

To all whom it may concern:

Be it known that I, WALTER F. KOKEN, a citizen of the United States, residing at St. Louis, Missouri, have invented a certain 5 new and useful Improvement in Pedestal-Bases for Barber-Chairs, of which the following is a full, clear, and exact description, such as will enable others skilled in the art to which it appertains to make and use the 10 same.

This invention relates to chairs of the kind that are used by barbers, dentists and other specialists, and particularly to barber chairs of the type which are provided with 15 a pedestal base formed of metal.

The type of metal base that is now universally used on barber chairs consists of a hollow casting comprising a base portion and a pedestal portion integrally connected 20 together and means on the base portion of the casting for sustaining the socket member of the chair that receives the stem which carries the seat frame. A cast metal pedestal base of the kind referred to is very 25 heavy, thus making the chair cumbersome to handle and expensive to ship from the manufacturer to the user, and such a base is costly to manufacture on account of the necessity of grinding off the outer surface 30 of the casting when the base is finished in porcelain enamel. Unless considerable skill and care are used in grinding off the outer surface of the casting preparatory to enameling it, the finished base will have a wavy or 35 irregular outer surface. If the chair manufacturer is not equipped with a large oven and is obliged to send the pedestal base casting to another city to be enameled, the cost 40 of transporting the casting is a large item in the complete cost of manufacturing the chair, due to the excessive weight of the casting.

The object of my invention is to provide a pedestal base for barber chairs, dentist 45 chairs and the like; that is light in weight and inexpensive to manufacture.

To this end I have devised a pedestal base for barber chairs and the like whose exterior or outer surface is formed by a sheet 50 metal shell, thereby producing a chair base that is light in weight; that can be manufactured cheaply in a die press and which can be finished in porcelain enamel without first grinding off the surface that is to be 55 coated with enamel.

Figure 1 of the drawings is a vertical sectional view of a chair base constructed in accordance with my invention.

Fig. 2 is a vertical sectional view, illustrating another form of my invention; and 60

Fig. 3 is a perspective view of one of the clips used to connect the rim of the base portion to the base casting of the supporting structure.

Referring to Fig. 1 of the drawings, 65 which illustrates one form of my invention, A, B and C designate three sheet metal members that coöperate with each other to form a shell comprising a substantially flat base portion and a vertically-disposed pedestal portion whose lower end flares outwardly and merges into said base portion.

The member A is of tubular form, the member C is flat or of substantially plate form and the intermediate member B is of 75 substantially frusto-conical-shape in general outline. A cap piece D is mounted on the upper end of the tubular member A, and a base rim E is combined with the horizontally-disposed member C in such a manner that it gives a finished appearance to the peripheral edge of the base.

All of the parts above referred to are preferably formed from sheet metal and they are carried by a supporting structure 85 composed of a base casting 1 that rests upon the floor and a socket member 2 that rests upon said base casting and projects upwardly from the center of same through the tubular member A of the pedestal portion 90 of the shell, said socket member being adapted to receive the vertically-adjustable stem of the chair (not shown) that carries the seat frame. It is immaterial how the base casting 1 and the socket member 2 are 95 formed and connected together, but one convenient way of combining said parts is to provide the base casting 1 with a center opening that receives the lower end portion of the socket member 2, said socket member 100 being provided with a laterally-projecting flange 3 or lugs that rest upon the base casting 1, as shown in the drawings. The horizontally-disposed sheet metal member C rests upon the base casting 1 and is provided 105 at its peripheral edge with a depending flange or downwardly turned portion 4 that laps over the peripheral edge portion of said casting, and thus holds said member C in concentric relation with said casting. 110

The intermediate member B of the sheet metal shell rests upon the member C and the tubular member A of the shell is supported by said intermediate member B.

- 5 The particular shape of the members A, B and C is immaterial and it is also immaterial how said members are combined or connected together. In the form of my invention shown in Fig. 1 the members A, 10 B and C are so constructed that one telescopes over the other, and the cap D and base rim E are used to clamp said members together and also clamp the horizontally-disposed member C to the base casting 1 15 of the supporting structure. When the members A, B and C are arranged in telescopic engagement with each other it is preferable to provide the horizontally-disposed member C with a large center opening 20 whose edge portion is turned upwardly so as to form a rim or flange 5 over which the lower end of the intermediate member B telescopes, and provide the member B at its upper end with an upwardly-projecting rim 25 or flange 6 that is arranged inside of the lower end of the tubular member A. The cap piece D is connected either to the socket member 2 or to the base casting 1 of the supporting structure in such a manner that 30 it can be drawn downwardly so as to force the members A, B and C tightly together. In the form of my invention shown in Fig. 1 the cap piece D is connected by means of screws 7 to laterally-projecting lugs 8 on 35 the socket member 2, and in the form of my invention shown in Fig. 2 the cap piece D is retained in position and drawn downwardly into snug engagement with the upper edge of the tubular member A by means of 40 long bolts 7^a that pass downwardly through the cap piece and are screwed into the flange at the lower end of the socket member. The base rim E is so formed that it laps over the peripheral edge portion of the horizon- 45 tally-disposed member C of the shell, and said rim is connected to the base casting 1 preferably by means of clips 9 secured to a laterally-projecting flange or lugs 10 on the base casting 1 and arranged inside of the 50 rim E, as shown in Fig. 1, each of said clips being provided at its inner end with a downwardly turned portion 9^a that bears upon the base casting and at its outer end with a downwardly turned portion 9^b that 55 bears on an inwardly-projecting flange 11 on the rim E. When the screws 10 are tightened the clips 9 will cause the rim E to be drawn downwardly, thereby securely clamp-

ing the member C of the shell to the base casting 1 of the supporting structure.

Instead of forming the sheet metal shell from three members, as shown in Fig. 1, said shell can be formed by a tubular member A and a base member F provided with an integral, upwardly-projecting portion F' 65 that tapers inwardly and merges into the tubular member A. The portion F' of the member F can either be arranged in telescopic engagement with the tubular member A, or said portion F' can be permanently 70 connected to the lower end of the member A by welding, the portion F' being provided at its upper end with a part 6^a on which the lower edge of the tubular member A rests.

A pedestal base of the construction above 75 described is considerably lighter in weight than the metal pedestal bases heretofore used on barber chairs, owing to the fact that it is composed, principally, of sheet metal. Accordingly, such a pedestal base effects a 80 considerable saving in the cost of transporting the chair from the manufacturer to the user. Furthermore, such a pedestal base can be manufactured at a low cost, as the sheet metal parts of same can be formed in 85 a die press and they can be finished in porcelain enamel without the necessity of first grinding off the surface to be coated with enamel.

Having thus described my invention, what 90 I claim and desire to secure by Letters Patent, is:

1. A pedestal base for chairs, comprising a supporting structure, a shell forming the exterior of the pedestal base and comprising 95 a base portion and a pedestal portion formed by a plurality of sheet metal members, a cap mounted on the upper end of said pedestal portion, a rim surrounding said base portion, and means for securing said cap and 100 rim to the supporting structure.

2. A pedestal base for chairs, comprising a base casting, a sheet metal shell forming the exterior of the pedestal base, and a base rim secured to said base casting and arranged so that it clamps a portion of said shell to said base casting.

3. A pedestal base for chairs composed of a base casting, a socket member mounted on said base casting, a sheet metal shell 110 that forms the exterior of the pedestal base, and means connected to said base casting and socket member for retaining said shell in operative position.

WALTER F. KOKEN.
